UNITED STATES PATENT OFFICE

163,941

CHAIR UNIT

Eugene C. Frost, Burbank, Calif., assignor to
Lockheed Aircraft Corporation, Burbank, Calif.

Application January 9, 1950, Serial No. 7,089

Term of patent 14 years

(Cl. D15—8)

To all whom it may concern:

Be it known that I, Eugene C. Frost, a citizen of the United States, residing in the city of Burbank, county of Los Angeles, State of California, have invented a new, original, and ornamental Design for a Chair Unit, of which the following is a specification, reference being had to the accompanying drawing, forming a part hereof.

Figure 1 is a side view of a chair unit, showing my new design;

Figure 2 is a front view thereof; and

Figure 3 is a rear quarter perspective view thereof.

In the drawings the dominant features of the design reside in the portions shown in full lines.

The opposite side of the arm portion is similar to that shown.

I claim:

The ornamental design for a chair unit, as shown and described.

EUGENE C. FROST.
